BOTTLE

Donald P. Denhoff and Dale R. Brown, Saline, Mich., assignors to Hoover Ball and Bearing Company, Ann Arbor, Mich., a corporation of Michigan

Filed July 27, 1961, Ser. No. 66,097

Term of patent 14 years

(Cl. D58—8)

The side not shown is the same as the side shown.

We claim:

The ornamental design for a bottle, as shown and described.
